DESIGN FOR A COOKING VESSEL

Kirk E. Porter, Wooster, Ohio, assignor to
The Buckeye Aluminum Company

Application November 7, 1946, Serial No. 134,574

Term of patent 3½ years

(Cl. D44—1)

To all whom it may concern:

Be it known that I, Kirk E. Porter, a citizen of the United States, residing in Wooster, in the county of Wayne, State of Ohio, have invented a new, original, and ornamental Design for a Cooking Vessel, of which the following is a specification, reference being had to the accompanying drawings, forming a part thereof.

Fig. 1 is a plan view of a cooking vessel, showing my new design;

Fig. 2 is a side elevational view; and

Fig. 3 is an end elevational view thereof.

The essential feature of the design resides in the handles shown in full lines.

I claim:

The ornamental design for a cooking vessel, substantially as shown and described.

KIRK E. PORTER.
